CAR CONSTRUCTION

Alfred C. Schmohl, Beaver Falls, Pa., assignor to
Pressed Steel Car Company, Inc., Pittsburgh,
Pa., a corporation of Pennsylvania

Application July 30, 1940, Serial No. 348,382

11 Claims. (Cl. 105—264)

My invention pertains to dump cars of the type having the body of the car tiltably mounted so as to provide for selective discharge of the lading at a side of the car, and more particularly to a mechanism for manually controlling selective tilting of the car body.

Tilting body dump cars fall into two general classes, i. e. those manually tilted and those tilted through the use of a fluid pressure medium or an equivalent mechanical force. My invention pertains to the manually operated tilting body dump cars. Usually this class of dump car is limited in scope to relatively small capacities because of the manual effort involved in moving the loaded body from normal lading receiving and transporting position into lading dumping or discharging position. As the lading capacity of these cars is increased obviously the manual effort involved in tilting the body proportionally increased and it has been heretofore necessary to employ two or more workmen in tilting the car body of 5 or more cubic feet capacity. Various types of bearings have been provided upon which the car body is supported for dumping, in order to reduce the manual effort involved in tilting the body out of normal position and returning same to that position. It was early recognized that to use a rocker bearing for supporting the tilting body, in place of spaced bearings, would reduce the manual effort involved in tilting the car body but would in turn introduce the problem of maintaining the car body in stable equilibrium on the underframe.

Latching means for retaining the rocker bearing mounted body in stable equilibrium were developed early in the art and where the body was mounted to tilt selectively about either side of the underframe, difficulties were encountered by way of having the bodies tilt to the wrong side of the underframe when the latches were released because of eccentricity in the loading of the lading within the car body or because of concentrated loading such as encountered where large stones or similarly concentrated weight formed a part of the lading. Likewise, as the capacity of the body was increased the need for manually operated dumping mechanisms arose and in the larger type bodies two or more dumping mechanisms began to be employed thereby necessitating a plurality of workmen, often two or more to one dumping mechanism, to tilt the body to discharging position and to return the body to normal position. Here again the problem of selective release of the latching mechanism to permit tilting of the body was encountered.

In my invention, as hereinafter set forth, I not only provide a solution for the difficulties encountered in the body supporting bearings and the latching mechanism but also a new and novel form of manually operated dumping mechanism, all of which are so assembled and coordinated on the car as to permit cars of relatively large capacity to be tilted and righted by a single workman or in the case of the use of plural mechanism, a single operator at each mechanism. The car hereinafter to be described and as disclosed in the drawings has a lading capacity of 108 cu. ft. of lading which weighs approximately 45,000#. Obviously the foregoing figures do not place a limit on the lading capacity of body for a car on which my invention can be used since any person skilled in the art after an examination of the disclosures herein can readily modify the mechanism within reasonable limits for any desired purpose.

One object of my invention is to provide a tilttable car body of the character described with a supporting bearing of a design providing a progressive lowering of the height of the center of gravity of a loaded car body as the body moves from normal to tilted position.

Another object of my invention is to provide a bearing of the character described which maintains the position of the center of gravity of the empty body in substantially a horizontal plane as the car body moves from dumping to normal position thereby facilitating the return of the body from dump to normal position with a minimum expenditure of manual effort.

Another object of my invention is to provide a latching mechanism which will maintain the body in stable equilibrium whilst the body is in normal or loading and transporting position and will also permit selective release of the latching means at one side of the body so as to permit tilting of the body to discharge the lading to the opposite side of the car and at the same time positively prevent undesired harmful tilting of the body in the opposite direction during any and all positions of the body in moving from normal to fully dumped position.

A further object of my invention is to provide a manually operated and controlled mechanism for moving the body from normal to dump position and for returning the body from dump to normal position.

A still further object of my invention is to so coordinate the latching and dumping mechanism so that when the latching mechanism is selectively released for tilting the body, the dumping

mechanism is automatically moved to operative position and when both latching means are in position to retain the body in normal position the dumping mechanism is rendered inoperative.

In the drawings forming part of this specification, Fig. 1 shows in end elevation a car of the character described having the body locked in normal position and with dumping mechanism rendered inoperative; Fig. 2 shows in side elevation a portion of the car of Fig. 1 illustrating the relative positions of the bearing, latches and dumping mechanism forming part of the present invention; Fig. 3 shows in full lines an end elevation of the car when in normal position similar to that shown in Fig. 1 of the drawings but having the latching mechanism at one side of the car released to permit the car to be tilted towards the opposite side of the underframe. This latter figure also illustrates the position of the dumping mechanism when moved to operative position and prior to any dumping movement of the lading body. On Fig. 3 and in dot and dash lines are shown three positions of the tilting body as it moves progressively from normal to tilted position and is returned; the first tilted position of the body illustrates the relationship between the tilting body and the dumping mechanism at the point during the tilting of the body where the dumping mechanism ceases to be effective in tilting the body; the lowermost tilted position of the body illustrates the relative position between the body, the underframe, and the body return portion of the tilting mechanism when the body is in extreme dump position; and the intermediate tilted position of the body illustrates the relative positions between the body and the body tilting mechanism at the point where the body return portion of the body tilting mechanism ceases to exert any effort upon the body in moving from dump to normal position.

Referring now to the drawings wherein like reference characters refer to like parts: A conventional form of car underframe is illustrated comprising spaced side sills 1 which are connected by suitable means such as end plates 2 and 3. This underframe is supported on any suitable wheel and axle assembly such as 4 connected to the underframe by means of bearings such as 5. At one or both ends of the underframe suitable provisions, such as indicated by the reference character 6, may be made for attachment of a coupling means should it be desired to operate these cars in train. Adjacent opposite ends of the underframe are provided body bearing supporting members such as 7 disposed transversely of the underframe and secured thereto. The form of the members 7 as illustrated, is a commercially rolled channel having both flanges disposed toward the adjacent end of the car and the web of the channel disposed in a vertical position. A suitably shaped car body 8 of the desired capacity is disposed above the underframe between the members 7 and supported on the latter by means of rocker bearings 9 mounted on each end of the car body and in engagement with the top flange of the adjacent member 7. These rocker bearings 9 include a rigid portion 10 having the outer face of the periphery thereof formed on a semicircle struck from a point slightly above the center of gravity of the empty lading body 8. It is this portion 10 of the bearing 9 which engages the upper flange of the adjacent transverse member 7 between the members 42 thereon and is

provided with suitable projections 11 engaging in suitable apertures in the upper flange of the member 7 to guide and maintain the members 9 and 7 in operative relationship as the body tilts in dumping. Intermediate the ends of the member 10 and projecting downwardly therefrom to overlap the member 7 is a member 12 secured to the member 10 to restrict relative movement between the member 10 and the member 7 longitudinally of the car when the body is in normal upright position. The member 10 is preferably secured to a base 13 of the bearing 9 as by welding and further suitably braced by ribs 14 and 15. Disposed across the member 7 between the upper and lower flanges thereof is a member 16 and a member 17, the members 16 and 17 forming a pocket within which the member 12 moves, and at the same time provides a vertical support for the member 7 to resist distortion from the weight of the lading within the body 8. Adjacent opposite ends of each member 7 are latch members 18 each having one end pivotally mounted on a pin 19 supported by a bracket 20 secured to the member 7. The opposite end of each latch 18, which is disposed above the member 7 and preferably inwardly of the pin 19, has a suitably shaped portion adapted to engage a pin 21 which is secured to the car body and preferably at the end of the portion 10 of the bearing 9. It will be obvious from an inspection of Fig. 1 of the drawings that when the latches 18 at opposite ends of the member 7 have their upper portions engaging the pins 21 adjacent each side of the car body 8, the body will be maintained in upright stable equilibrium and cannot be tilted toward either side of the car until after one of the latches 18 have been moved to release position, as illustrated in Fig. 3.

The mechanism provided for tilting the car body comprises a lever 22 and a latch 23, both pivotally mounted on the latch 18 by means of a common pin 24. This latch 23 depends below the pin 24 and has an aperture 25 extending longitudinally thereof and terminating in an offset portion 26. Mounted on the adjacent member 7 is a bracket 27 extending upwardly from the member 7 and adjacent the latch 23. A suitable pin 28 is secured on the bracket 27 and extends into the aperture 25 of the latch 23. This pin 28 is disposed adjacent the uppermost portion of the aperture 25 in the latch 23 when the body latch 18 is engaged with the pin 21 of the rocker bearing 9, as indicated in Fig. 1 of the drawings. The lever 22, which is likewise mounted on the latch 18 by means of the pin 24, has a top portion 29 extending upwardly and outwardly from the pin 24 to a point toward the adjacent side of the body 8 when the latter is in normal position. The major portion of the lever 22 depends below the pin 24 and terminates in a handle portion 30, the distance of the handle portion 30 of the latch from the pin 24 being determined by the amount of effort necessary to tilt the car body. The handle 30 is preferably disposed outwardly of the side of the car underframe to prevent interference therewith, as illustrated in Fig. 1 of the drawings. A pin 40 mounted on latch 18 above pin 19 engages lever 22 to limit inward movement of lever 22, as illustrated in Figs. 1 and 3.

The outermost top face of the portion 29 of the lever 22 is preferably curved and shaped so that the outermost end portion of the head 29 will lie below a bearing bar 31, mounted on the side 75 of the car body by any suitable means such as the

bracket 32 as shown in Fig. 1 of the drawings and when the lever 22 is moved to operative position, as shown in Fig. 3 of the drawings, the head 29 will move freely beneath the bar 31. The lever 22 in the form shown in Figs. 1 and 2 is provided with a suitable offset 33 and brace 34 to clear the head of pin 19. It will be obvious that this is merely a detail of construction necessitated by the relative positions of the latch 18, lever 22, and pin 19. In order to retain the latch 23 in position on the pin 24 in the latch 18 I have provided suitable means such as the member 35 which is rigidly secured to the lever 22 and has an aperture in one end thereof into which the pin 24 extends. The end of the pin 24 is preferably threaded and a bolt 36 mounted on the threaded portion of the pin 24 secures the latches 18 and 23 and the lever 22 in fixed pivotal relationship through the pin 24.

The number of tilting mechanisms provided on each car will vary with the lading capacity of the car body and the manner of using the cars. Where the capacity is very large and the body is tilted selectively to either side of the underframe, four tilting mechanisms may be provided, one on each latch 18 as shown on Fig. 1 of the drawings. In the case of smaller cars but two tilting mechanisms may be used and disposed on diagonally opposite ends of the car body. Obviously, in the case of car bodies tilting in one direction only, the tilting mechanisms will be mounted at but one side of the car and at one or both ends as found desirable.

Whilst I prefer in the larger sized cars to provide a lever 22 on each latch 18, I have found that even in the cases where the body tilts selectively about opposite sides of the car underframe I need to provide but one body righting mechanism at each end of the car and to mount these body righting mechanisms at diagonally opposite ends of the car. This is done because but one body righting mechanism is usually necessary to right the body by reason of the bearing support used and also when mounting the righting mechanisms at opposite ends of the body interference between righting mechanisms is avoided. The righting mechanism is preferably mounted on one of the pins 19, such as 19^a, and is preferably disposed behind the member 7, as indicated in Fig. 2 of the drawings. This righting mechanism comprises a lever 37 having its upper portion suitably apertured and mounted on the pin 19^a. This lever 37 depends from the pin 19^a and extends below the lower edge of the member 7 for a purpose hereinafter described. Intermediate the ends of the lever 37 is rigidly fastened one end of a lever 38 which extends transversely of the car underframe and when the body is in normal position rests upon the underframe at the side thereof opposite the lever 37. The free end of the lever 38 terminates in a suitable handle portion 39. The normal positions of the levers 37 and 38 are as illustrated in Fig. 1 of the drawings. When, however, the body is in fully tilted position, as shown in Fig. 3 by dot and dash lines marked with the reference character 8^a, the bar 31 engages the lever 37 causing it to rotate inwardly on its pin 19^a into the position marked 37^a thereby causing the lever 38 and its handle 39 to move into the position indicated by dot and dash lines on Fig. 3 and marked with reference characters 38^a and 39^a.

In describing the operation of the car reference is first made to Fig. 1 of the drawings wherein the body 8 is shown in normal position with latches

18 on opposite sides of the underframe and at each end of the car body engaging pins 24 at opposite sides of the bearing 9 to lock the body in normal position and to prevent tilting of the body towards either side of the underframe. In this position of the latches 18 the car dumping mechanism is rendered inoperative for it will be obvious that if the operator grasps the handle portion 30 of the lever 22 and rotates the lever 22 upwardly, the portion 29^a of the head 29 of the lever 22 will pass beneath the pin 31. It is likewise of importance that when the levers 22 have their head portions 29 disposed in the position illustrated in Fig. 1 of the drawings the bar 31 is out of engagement with the end portion 29^a of the head of the lever 22 and prevents any interference between the tilting body and the lever 22. Whenever it is desired to tilt the car body to one side of the underframe, for example to the left side of the underframe as illustrated in Fig. 3 of the drawings, the operator grasps the pin 41 in the head of the latch 18 at the right hand side of the underframe and rotates the latch 18 upwardly and outwardly towards the right side of the car body into the position illustrated in Fig. 3 of the drawings. During this rotation of the said latch 18, the latch 23 pivoting on the pin 24 secured on the latch 18 moves upwardly and outwardly until the pin 28 approaches the end of the aperture 25 in the latch 23 and thereafter moves into engagement with the offset portion 26 of the aperture, as illustrated on the right side of Fig. 3 of the drawings. Under normal conditions the latch 23 will rotate downwardly by gravity to move aperture offset 26 into engagement with the pin 28 to retain the latches 18 and 23 and the lever 22 in the positions as shown in Fig. 3 of the drawings. If this gravitational movement does not occur it will be a simple matter for the operator to manually move the latch 23 into the latter described position.

As illustrated in Fig. 3 of the drawings the latch 18 is now locked in its elevated position by means of the latch 23 and pin 28 and, likewise, the head 29 of lever 22 has moved beneath the bar 31 fastened at the right side of the car body. If during this described movement of the latch 18 there should be any interference between the head 29 of the lever 22 and the bar 31, it is obvious that the lever 22 is free to pivot on the pin 24 so as to lower the head 29 of the lever 22 to permit movement thereof beneath bar 31. Under normal circumstances the lever 22 will normally move by gravity so as to depress the head 29 of the lever 22, but if this does not occur engagement with pin 31 will produce the desired results.

From an inspection of Fig. 3 of the drawings it will now be obvious that the car is free to be tilted toward the left side of the underframe, as viewed in Fig. 3. The operator, grasping handle 30 of lever 22 on the right side of the car, now pulls upwardly causing the lever 22, rotating on pin 24, to move head 29 of the lever 22 upwardly and inwardly of the car in engagement with bar 31. This movement of head 29 on pin 31 causes the car body to move to the left for as long as the bar 31 is in engagement with the head 29 of lever 22, all as illustrated in dot and dash lines on Fig. 3, or until the car body moves into the position marked 8^b which illustrates the point during the tilting of the body where the bar 31 moves out of engagement with head 29 of the lever 22 with the continued

tilting of the car body. During movement of the body from normal position into that marked by the reference character 8^a the body has acquired sufficient momentum to carry it on over into fully dumped position, as illustrated in dot and dash lines on Fig. 3 and marked with the reference character 8^a .

It will be recalled, as previously stated, that the portion 10 of the bearing 9 is formed on a semicircle struck from a point slightly below the center of gravity of the empty body, which is indicated by the reference character A on Fig. 3 of the drawing. Obviously, therefore, the portion 10 of the bearing 9 moving along the top face of the member 7 will tend to carry the center of gravity of the empty body along a substantially straight line until the point A reaches the point C , which is the position of the center of gravity of the empty body when the body is in fully tilted position. It will likewise be obvious that the center of gravity of the loaded body will be above the point A and will move outwardly and downwardly to the point C along a path marked by dot and dash lines connecting points B and C as the lading progressively passes out of the body during movement of the body from normal position to fully dumped position as indicated in dot and dash lines and marked with the reference character 8^a . From a comparison of the lines AC and BC on Fig. 3 it will be apparent that any momentum built up in the body moving from the normal position to dumped position will be sufficient to carry the body from the position marked 8^b to the position marked 8^a without any assistance from the lever 22 .

Referring now to the position of the fully tilted body, indicated by the reference character 8^a on Fig. 3 of the drawings, it will be observed that in this position of the body the bar 31 has moved the lever 37 into the position marked 37^a and moved the lever $38-39$ into the position marked 39^a in Fig. 3 of the drawings. Therefore, when the operator is ready to right the body he grasps the handle portion 39^a of the lever 38 , rotating it downwardly upon the pin 19^a , to move the lever 37 outwardly until the lever 38 engages the underframe, which is the position of the lever 38 indicated by full lines on Fig. 3 of the drawings. During this movement of the levers 37 and 38 , the lever 37 in engagement with the pin 31 has moved the body into the position indicated by dot and dash lines on Fig. 3 of the drawings and marked with the reference character 8^c . It will be obvious that on account of the previously described construction of the bearing 9 the momentum built up in the body during its passage from position marked 8^a to that marked 8^c will be sufficient to cause the body to continue until it reaches normal position and, if for any reason the body should not continue on to normal position, a very slight force exerted by the operator on the body will cause it to complete its movement to normal position, which is illustrated by full lines in Fig. 3 of the drawings.

When the body reaches the position as illustrated in full lines on Fig. 3 of the drawings, the pin 21 at the left side of the gearing 9 engages the adjacent latch 18 and prevents further rotation of the body. At this point the operator then grasps latch 23 at the right side of the body, rotating it upwardly until pin 28 moves into engagement with aperture 25 in latch 23 , and thereafter the latch 18 at the right side of the body

will move downwardly by gravity and the weight of lever 22 and latch 23 , until this latter latch 18 engages the pin 21 , thereby locking the body in normal upright position.

Obviously where it is desired to discharge lading to the right side of the car underframe, the same procedure is followed except that the dumping mechanism at the left side of car is used.

Throughout this specification and in the drawings I have described and shown what I now consider a preferred form of construction, it will however be apparent to those skilled in the art that various modifications may be made in the form and arrangement of the various members and I do not intend to limit myself to the exact forms of construction and arrangement herein except as made necessary by the scope of the appended claims.

Having thus described the invention what I claim as new and desire to secure by Letters Patent is:

1. In a tilting body dump car, in combination, an underframe, a lading body, bearings at each end of the body each having an arcuate surface extending outwardly from the end of the body for engagement with the underframe to support the body for tilting movement thereon and so disposed beneath the horizontal plane of the center of gravity of the empty body in normal position as to maintain same substantially within said horizontal plane throughout the major portion of the tilting movement of the body in opposite directions from normal upright position, latch means mounted on the underframe adjacent opposite sides thereof for selective engagement with suitable portions on the body to lock the body in normal upright position and releasable therefrom to permit tilting of the body to a preselected side of the underframe, means mounted on each latch means for retaining the respective latch in released position and rendered inoperable by manual movement of the latch out of released position, and including a portion pivotally movable in respect to the latch when in released position for tilting the car body from normal to dump position, and additional means mounted on the car underframe for engagement with the tilted body and rendered operative through said engagement therewith for imparting a righting impulse to the tilted car body.

2. In a tilting body dump car, in combination, an underframe, a tiltable lading body, bearings at each end of the body, each said bearing having an arcuate surface extending outwardly from the adjacent end of the body for engagement with the underframe to support the body thereon in tiltable relationship and so disposed beneath a horizontal plane through the center of gravity of the empty body as to maintain same substantially within said horizontal plane throughout the major portion of the movement of the body in tilting in opposite directions from normal upright position, latch means mounted adjacent opposite sides of the underframe at each end of the car body for selective engagement with suitable portions on the body to lock the body in normal upright position and selectively releasable therefrom for permitting the tilting of the body to a preselected side of the underframe, means mounted on each said latch means and rendered operable by movement of the latch to release position to retain the respective latch in released position, and including a portion pivotally movable in respect to the latch when in

release position for tilting the car body from normal toward dump position.

3. In a manually operated tilting body dump car, in combination, an underframe, a tiltable body, bearing means secured to each end of the body and engaging the underframe to support the body on the underframe in unstable equilibrium, latch means movably mounted on the underframe and selectively engaging with the body to maintain the body in stable equilibrium and selectively releasable from engagement with the body to permit tilting of the body toward a preselected side of the underframe, and a body tilting mechanism mounted on each said latch for movement relative to the latch and in engagement with the body to impart a tilting impulse to the body.

4. In a manually operated tilting body dump car, in combination, an underframe, a body, bearing means at opposite ends of the body supporting same upon the underframe in unstable equilibrium for selective tilting toward opposite sides of the underframe, latch means mounted on the underframe adjacent opposite ends of the body for selective engagement therewith to retain the body in stable equilibrium and selectively releasable from engagement therewith to permit tilting of the body to a preselected side of the underframe, manually operated body tilting mechanisms mounted on each said latch means for movement relative to the latch means and in engagement with the body for imparting a tilting movement to the body to discharge lading, said body tilting mechanism including a portion operably connected with the car underframe for selective movement relative thereto to maintain its respective latch means in release position whilst the dumping mechanism is imparting a tilting movement to the car body and selectively movable relative to the underframe to permit engagement of the latch means with the car body and disengagement of the tilting mechanism from the car body.

5. In a manually operable tilting body dump car, in combination, an underframe, a tiltable body, bearing means supporting the body on the underframe in unstable equilibrium for selective tilting movement towards a preselected side of the underframe, latch means mounted on the underframe at opposite ends of the body for selective engagement with an adjacent portion of the body to maintain the body locked in stable equilibrium and selectively movable to release the body for tilting in a single preselected direction, manually operable body tilting mechanism mounted on each said latch means in a position whereby the tilting mechanism is rendered inoperative whilst the latch means is in engagement with the body and automatically rendered operable when the associated latch means is moved to release position, said tilting mechanism including a portion movable relative to the latch means and the body whilst the tilting mechanism imparts tilting movement to the car body, and a member mounted on the body and disposed in the path of movement of the tilting mechanism for engagement therewith during the time the tilting mechanism is imparting a tilting movement to the car body.

6. In a vehicle of the character described, in combination, an underframe, a tiltable body, bearing means at opposite ends of the body for engagement with the underframe to support the body on the underframe in unstable equilibrium, 75

latch means pivotally mounted adjacent opposite sides of the underframe at each end of the body for selective engagement with the body to lock the body in stable equilibrium on the underframe and selectively releasable from engagement with the body to permit tilting thereof towards a preselected side of the underframe, body tilting mechanisms mounted on one of the latch means at each end of the body and at diagonally opposite sides of the underframe for selective independent movement to impart tilting movement to the car body, each said mechanisms including a portion associated with an adjacent portion of the underframe in a manner operating to lock the associated latch means in release position and rendered inoperable when the said latch is in engagement with the car body for locking same in stable equilibrium, a member mounted on the body adjacent each said mechanisms for engagement therewith whilst said mechanism is imparting tilting movement to the car body, said mechanism being moved out of engagement with said body member when the associated latch means is moved into engagement with the car body and being moved into position to engage said body member when the latch means is moved out of engagement with the car body.

7. In a vehicle of the character described, in combination, an underframe, a tiltable body, bearing means at opposite ends of the body for engagement with the underframe to support the body on the underframe in unstable equilibrium, latch means pivotally mounted adjacent opposite sides of the underframe at each end of the body for selective engagement with the body to lock the body in stable equilibrium on the underframe and for selective release from engagement with the body to permit tilting thereof towards a preselected side of the underframe, body tilting means mounted on one of the latch means at each end of the body and at diagonally opposite sides of the underframe for selective independent movement to impart tilting movement to the car body, each said mechanisms including a portion associated with an adjacent portion of the underframe in a manner operating to lock the associated latch means in release position and rendered inoperable when the said latch is in engagement with the car body to lock same in stable equilibrium, a member mounted on the body adjacent each said mechanisms for engagement therewith whilst the mechanism is imparting tilting movement to the car body, said mechanism being moved out of position to engage with said body member when the associated latch means is moved into engagement with the car body and moved into position to engage said body member when the latch means is moved out of engagement with the car body, and means mounted on the underframe at each end of the car body at a side of the underframe opposite the tilting mechanism for imparting a righting movement to the fully tilted car body, said means extending across the underframe to adjacent the tilting mechanism and normally disposed in inoperative position whilst the body is in upright stable equilibrium, said latter means being engaged by the tilting body and moved to operative position as the body approaches the end of its tilting movement about the adjacent side of the underframe.

8. In a dump car having an underframe and a body supported thereon for tilting toward a side thereof, a body tilting device comprising fulcrum means including a member pivoted to the car

underframe adjacent one side thereof and a latch member pivoted to said first-named member, a body tilting lever pivotally connected intermediate its ends with said fulcrum means and having one end of the lever turned outwardly from said pivotal connection, means on said fulcrum means latch member for engaging with the underframe to selectively support the fulcrum means in raised and lowered position, and a means on said body adapted to be engaged by said outwardly turned portion of the body tilting lever for tilting the body when the lever is rotated with said fulcrum means in raised position.

9. In a dump car including an underframe and a lading body mounted thereon for tilting toward a side thereof, in combination, a fulcrum member pivoted at one end to the car underframe adjacent one end of the car body, a latch member pivoted at one end to said fulcrum member adjacent the free end of said fulcrum member, means on said latch member adjacent the free end thereof for selective engagement with the underframe to support the fulcrum member in raised and lowered relation with the underframe, a lever member supported intermediate its ends by said latch and fulcrum members and pivotally connected therewith, a head portion on said lever lying adjacent an end wall of said body above the pivotal support for the lever, a member mounted on the body and projecting beyond said end wall thereof above said head portion of the lever, said lever head portion engaging said body member to tilt the body when the lever is rotated whilst in raised position and passing beneath the member on the body when the lever is rotated in lowered position.

10. In a dump car including an underframe and a lading body supported thereon for alternate tilting toward opposite sides thereof, the combination of a fulcrum member pivotally mounted on the underframe adjacent each end thereof and projecting above same, a latch mem-

ber pivotally connected with each fulcrum member and depending toward the underframe, cooperating means on each said latch member and adjacent portion of the underframe for selectively supporting the fulcrum and associated latch members in raised and lowered positions, a body tilting lever pivotally connected with each said latch and fulcrum members and having head and handle portions normally extending respectively above and below said pivotal connection between the lever and said members, members mounted on the body and projecting outwardly from each end wall thereof, said head portion of the body tilting lever engaging with an adjacent body member to impart a tilting movement to the body when the lever is rotated whilst in raised position and being rendered inoperative when the lever is in lowered position.

11. In a dump vehicle including an underframe and a lading body supported thereon for selective tilting toward opposite sides of the underframe, in combination, a fulcrum means mounted on the underframe adjacent each end of the car body and adapted to be selectively secured in raised and lowered position in relation to said body, a body tilting lever pivotally mounted on each said fulcrum means and each lever having a head portion disposed adjacent an end of the car body, members mounted on the car body and projecting outwardly from each end thereof above each said lever head portion, said fulcrum means at one end of the car body when in raised position disposing the head portion of its associated lever in position beneath said body member to engage therewith to tilt the car body in one direction when the lever is rotated, and said fulcrum means when in lowered position disposing the lever head portion below the body member and out of position to engage therewith when the body is tilted in the opposite direction.

ALFRED C. SCHMOHL.
